UNITED STATES PATENT OFFICE.

CARL HAMBUECHEN, OF BELLEVILLE, ILLINOIS, ASSIGNOR, BY MESNE ASSIGNMENTS, TO NATIONAL CARBON COMPANY, INC., OF CLEVELAND, OHIO, A CORPORATION OF OHIO.

HAND-LAMP.

1,388,948.

Specification of Letters Patent. Patented Aug. 30, 1921.

Application filed April 27, 1917. Serial No. 164,833.

To all whom it may concern:

Be it known that I, CARL HAMBUECHEN, a citizen of the United States, residing at Belleville, in the county of St. Clair, State 5 of Illinois, have invented certain new and useful Improvements in Hand-Lamps; and I do hereby declare the following to be a full, clear, and exact description of the invention, such as will enable others skilled in the art 10 to which it appertains to make and use the same.

The present invention relates to battery and hand lamps, and more particularly to the form and arrangement of the electrical 15 conductors used therein.

Battery hand lamps, especially those in the form of relatively long cylindrical torches, are usually provided with switch mechanism operative from the outside of the 20 casing and co-operating with a metallic strip or strips within the casing and forming part of the lamp circuit. The battery is contained in a paper or pasteboard carton and housed within the tubular casing. When the battery 25 containers become perforated through use or age, it frequently happens that the liquids thereof permeate the paper carton and in time corrode the metallic conducting strips within the casing of the apparatus. 30 Also, the batteries are inclined to swell and become stuck in the casing, and their forcible removal is liable to disarrange the conductive strips and even tear them from their fastenings within the casing.

It is an object of the present invention to 35 eliminate the possibility of corrosive action upon the conducting strip or strips by placing it, or them, outside of the battery chamber. This I am able to do with economy and 40 convenience and with a marked increase in the reliability of the apparatus. A modified form of the invention eliminates entirely from the battery chamber of the casing all metal which might be corroded by 45 the fluids from the battery.

Other objects and advantages of the invention will be apparent from a description of certain preferred embodiments thereof, as illustrated in the accompanying drawings, in which—

Figure 1 is a view of the exterior of a battery hand lamp showing the invention applied thereto;

Fig. 2 is a view partly in section of the same lamp;

55

Fig. 3 is a transverse section along the line 3—3 of Fig. 2;

Fig. 4 is a view of the exterior of a modified form of the invention;

Fig. 5 is a view partly in section of the 60 hand lamp shown in Fig. 4; and

Fig. 6 is a transverse section along the line 6—6 of Fig. 5.

Referring to the drawings, in which similar reference characters denote similar parts 65 throughout the several views, 10 represents a casing constructed of any desired insulating material such as fiber. At the front end of the casing is a sleeve 11 provided with screw-threads by which a collar 12 is attached. The collar serves to clamp in place 70 a lens 13 and a metallic reflector 14, the outer rim of which is clamped between the end of the fiber casing and the lens. The reflector is provided at its base with a screw- 75 threaded socket adapted to receive a small incandescent lamp 15. The reflector thus constitutes a part of the lamp circuit. The inner terminal 16 of the lamp engages a terminal 17 of the battery 18, these two terminals being held in contact by a spring 19 80 which engages the other end of the battery and is held in place by a cap 20 screw-threaded upon a sleeve 21 attached to the rear end of casing 10. The battery may be 85 of usual construction comprising a plurality of cells arranged end to end and inclosed in a paper or pasteboard carton. The pressure of spring 19 maintains good connection 90 throughout this series of cells. Spring 19 is in contact with a naked zinc container which forms the other terminal of the battery and the circuit from the spring is continued through the cap 20, sleeve 21 and a 95 conducting strip 22 placed within a channel on the outside of casing 10 and having one end retained in place beneath sleeve 21, as shown most clearly in Fig. 2. The other end of strip 22 is placed beneath, and contacts with, a metallic plate or shield 23 attached to the casing by means of rivets 24. A rivet 25 passes through plate 23, strip 22 100 and the wall of the casing.

The metal plate 23 serves as the base for a sliding thumb piece 26 which is retained 105 in place upon the metal plate by means of

pins 27 which pass through slots 28 in the metal plate. Beneath the metal plate these rivets 27 pass through a conducting strip 29 which is laid within a channel on the outside of casing 10 and passes under sleeve 11 and makes electrical contact with reflector 14. In Figs. 1 and 2 the sliding thumb piece is shown in the open circuit position in which position the rivets 27 are at the rear ends of the slots 28. When the thumbpiece is moved along the metal plate 23 toward the front end of the lamp, conducting strip 29 is moved along through its channel in the exterior of the casing until its forward end 15 comes into contact with the rim of the reflector 14, thus establishing the lamp circuit from the terminal 17 of the battery through the terminal 16 of the lamp, through the filament of the lamp and the outer socket 20 thereof, thence through the metallic reflector, conducting strip 29, and plate 23, against which the conducting strip is held by the rivets 27, thence through the conducting strip 22 to the sleeve 21, cap 20 and spring 25 19 to the other terminal of the battery. As long as the thumb piece is held in its forward position the lamp circuit will be closed. The only parts of the construction described above which lie within the casing 30 and which may be corroded under the action of any liquids which leak out of the battery are the heads of rivets 24 and 25, but these are of comparatively small area and there is little or no chance that they will be seriously affected by the corrosive action of this liquid. If desired, these rivets may be of insulating material and strip 22 may be soldered to collar 21 and to plate 23. In the modification illustrated in Figs. 4, 5 and 6, 35 the fiber tube, the sleeves, collars, the lens, reflector, lamp, battery and retaining spring are of the same general construction as in the other figures. In this construction, a conducting strip 30 is attached to the under side of the rear sleeve 21, as by means of a rivet 31, and extends along the exterior of the tube. The strip may be of rounded cross-section, as shown in Fig. 6, with its edges set into and protected by shallow 40 grooves in the fiber tube, and terminates in a shield or plate provided with an integral switch-housing 32. The shield is attached to the outer surface of the fiber tube by means of rivets 33 which preferably are so 45 far forward as to be out of the battery chamber of the casing and so not exposed to danger of corrosion in case of battery leakage. The top of the switch-housing is provided with a slot 34 through which 50 passes the shank of a button or thumbpiece 35 having at its lower end a folded contact spring 36 which is considerably wider than the slot 34 so that it will not spring upwardly through the latter. The contact 55 spring 36 is provided with two indentations,

one or the other of which may snap over a fiber stud 37 to hold the contact spring in either of two positions. Other forms of switch mechanism may here be used with equally good results.

For the purpose of completing the lamp circuit, a conducting strip 38 is laid along the inside of the lamp chamber at the front end of the tube, and has its forward bent end clamped between the edge of the fiber tube and the rim of the reflector. The other end of this conducting strip extends through an aperture in the tube and is hooked over the outside thereof to retain it firmly in position.

In order to complete the circuit of the lamp it is only necessary to push the button 35 and with it the contact spring into a position such that the folded edge of the spring engages the bent-over portion of conducting strip 38 in which position the second depression of the contact strip will snap over stud 37 to aid in retaining the contact spring in its circuit-closing position. The action of the depressions in the contact springs and the stud 37, while sufficient to prevent the contact spring from being accidentally displaced when the lamp is being carried, will not, however, interfere with the convenient manipulation of the push button to make or break the circuit of the lamp.

In this embodiment of the invention, there is no metal part within the battery chamber of the tube and exposed to accidental corrosion. While the conducting strip 38 lies within the casing, it is within the lamp chamber, and so is beyond the reach of corrosive liquors leaking out of the dry cells and wetting their paper envelop.

If the lamp is being carried in a tool box or other place where its metallic fittings may come in contact with tools or other conducting devices there will be no danger of the lamp being accidentally lighted since the edge of reflector 14 through which lamp current is conducted is surrounded by collar 12 and cannot come in contact with any extraneous metal. The lamp is therefore non-short-circuiting in the sense that the batteries cannot become accidentally exhausted.

While two embodiments of the invention have been shown it will be understood that various other changes may be made in the details of construction without departing from the principle of the invention.

I claim:

1. In a hand lamp a tubular insulating casing having a battery chamber, a battery fitting closely within said chamber, a metallic cap on one end of the casing for retaining the battery in place thereon, said cap being electrically connected with one terminal of the battery, a metallic reflector at the other end of the casing, a lamp mounted in the reflector, and connected to the other ter-

- terminal of the battery, and means for controlling the circuit through said lamp, said means comprising a conducting element movable into and out of engagement with the reflector, an actuating member for said conducting element, and a second conducting element mounted upon the exterior of said casing between said cap and said actuating member.
2. In a hand lamp a tubular insulating casing having a battery chamber therein, a battery within said chamber, a sleeve upon one end of the casing, a metallic cap screwed upon the sleeve for retaining the battery in place and electrically connected with one terminal of the battery, a metallic reflector at the other end of the casing, a lamp mounted in the reflector and connected to the other terminal of the battery, and means for controlling the circuit through said lamp, said means comprising a conducting element movable into and out of engagement with the reflector, an actuating member for said element, and a second conduct-
ing element fixed upon the exterior of the casing between said cap and said actuating member.
3. In a hand lamp, an insulating tube forming a battery chamber, a battery therein, a lamp connected with one pole of said battery, a reflector for said lamp, and switch mechanism for connecting the other pole of said battery with said reflector, said mechanism including a contact element positioned outside of said battery chamber and movable into and out of contact with said reflector.
4. In a hand lamp, an insulating tube forming a battery chamber, a battery therein, a lamp connected with one pole of said battery, a reflector seated on the end of said tube and insulated thereby and formed with a socket for the reception of the lamp, and switch mechanism for connecting the other pole of said battery with said reflector, said mechanism including a contact strip positioned outside of said battery chamber and movable longitudinally of said tube into and out of contact with said reflector to control the flow of current from the battery to the lamp.

In testimony whereof I affix my signature.

CARL HAMBUECHEN.
